UNITED STATES PATENT OFFICE.

RALPH ADOLPHUS WAXLER AND EUGENE SAPP, OF LAWRENCEVILLE, ILLINOIS.

STILL.

1,200,281.

Specification of Letters Patent.

Patented Oct. 3, 1916.

Application filed November 30, 1915. Serial No. 64,233.

To all whom it may concern:

Be it known that we, RALPH A. WAXLER and EUGENE SAPP, both citizens of the United States, and residents of Lawrenceville, in the county of Lawrence and State of Illinois, have invented a new and Improved Still, of which the following is a full, clear, and exact description.

Among the principal objects which the present invention has in view are: to provide for accelerating the vaporization of heavy oil that the lighter ingredients thereof may be separated therefrom; to provide means for preventing the injurious accumulation of mineral or base products; and to provide simple and efficient mechanical means for accomplishing the objects stated.

Drawings.—Figure 1 is a vertical longitudinal section of a still constructed and arranged in accordance with the present invention, the section being taken as on the line 1—1 in Fig. 3; Fig. 2 is a longitudinal section on an enlarged scale, the section being taken as on the line 2—2 in Fig. 3; Fig. 3 is a cross section on an enlarged scale, the section being taken as on the line 3—3 in Fig. 1; Fig. 4 is a detail view on an enlarged scale showing one of the tube-scraping disks with which the still is provided.

Description.—The herein described still is employed principally for the reduction of crude or heavy oils wherein the lighter volatiles may be liberated by what is known as destructive distillation, or by breaking down the constitution of the original material. To this end it is desired that the oil should be subjected to heat for a predetermined period, and that the vapors should be collected and recovered by condensation after the heavy or base particles have been removed and permitted to settle. With this object in view, the heating domed chamber 9 is interposed between the fire box 10 and the smoke flue 11, from which extends a pipe 12. The chamber 9 is provided, at the upper and lower ends thereof, with arches 13 and 14, which arches are formed from refractory material, which material is also used for lining the box 10 and flue 11, as seen best in Fig. 1 of the drawings. Between the box 10 and flue 11, is placed a fire wall 15, also constructed from refractory material and supported by the arch 14. The wall 15 extends completely across the chamber 9 and compels the heated gases delivered from the box 10 to pass upward through the said chamber

before being delivered therefrom to the flue 11.

The oil treated in the present still is primarily delivered from a supply to a receiving tank 16. The tank 16 is suspended in a chamber 17 below the arch 14, and so removed from the influence of the heat generated in the box 10. The tank 16 is thus suspended by pipes 18, which extend through suitable perforations in the arches 13 and 14 and are bolted to short nipples 19 screwed or otherwise rigidly secured in a delivery tank 20 above the arch 13. The tank 20 rests directly upon the supporting angle irons 21, forming part of the furnace structure in which is incorporated the box 10, flue 11, and chamber 9. The pipes 18 are provided at the ends of each, with bolting flanges 22, which are secured to bolting flanges 23 and 24 formed on the nipples 19 and 25, the latter being rigidly secured in the tank 16.

When the flanges above enumerated are securely united, it will be found that the tanks 16 and 20 and pipes 18 connecting the same, are supported upon the angle irons 21, the said tanks being protected from the hot gases in the chamber 9 while the pipes 18 communicating between the two tanks are directly subjected thereto.

The tank 16 receives the oil for treatment by supply pipe 26. The oil is supplied to the tank 16 under pressure, the pressure being produced and regulated by any suitable and conventional means. As seen best in Fig. 1 of the drawings, the oil is delivered to the tank 16 near the top thereof. In this manner, provision is made for the precipitation or separation of the residuum, coke or carbon contained in the oil or resulting from the treatment thereof while passing through the pipes 18. This residuum is returned to the tank 16 and settles therein to the bottom thereof. To remove the residuum above mentioned, a manhole having a cap 37 is provided.

The tank 20 collects the lighter elements of distillation and is provided with a series of gage cocks 28 and a dome 29 from which the lighter vapors or volatiles are carried off by a pipe 30. The pipe 30 is inclined and passes through a water-cooling jacket 31, where the vapors or gases are sufficiently condensed to descend the pipe 32 to the radiating coils 33, which are mounted in a cooling bath 34 of conventional form and construction. The coils 33 and bath 34 are ar-

ranged to condense the gases and cool the liquid delivered by the pipe 32, which are delivered thence by a pipe 35, to a separating drum 36. From the drum 36, finished oil is passed for removal by way of the gage 40, while the residuum is drawn from the drum by the pipe 38, the delivery of the carbon products being controlled by the valve 39. Pipe 37 leads to a pressure gage. 10 The sight gage 40 is connected with the drum 36 for ascertaining the quality of the product delivered thereto from the still, said gage having a transparent panel 41 through which the passing liquid therein may be viewed. The crude or heavy oil delivered to the tank 16, is lifted therefrom to the pipes 18. Sufficient heat is generated in the box 10 and chamber 9 to break down the oil for separating the lighter and more gaseous elements from the base elements. 15

It becomes necessary, in order that the pipes 18 shall not be clogged, to remove the coke. To accomplish this, there is employed in each pipe 18, a vibrating rod 42. The 20 rods 42 are suspended in pairs, the members of each pair being suspended by a connecting beam 43. The connecting beams 43 are each rigidly mounted on a rocking shaft 44 disposed within the tank 20 and supported 25 therein by a bearing standard 45 adjacent one end of said tank and a stuffing box 46 disposed at the opposite end of said tank. The shaft 44 extends beyond the stuffing box and is provided with a crank handle 47 30 to be employed for rocking the said shaft either manually or by means of power machinery of any conventional and approved type. To maintain the straight-line arrangement of the rods 42, braces 48 are 35 extended lengthwise of the tank 20.

At intervals equaling somewhat less than the stroke of the rods 42, are disks 49, which slidably fit the pipes 18, bearing 40 lightly against the inner surface thereof to maintain the same clear of foreign deposit. The disks 49, as seen best in Fig. 4 of the drawings, are provided with a series of perforations 50, through which the oil passes as the disks and their rods are raised and 45 lowered in said pipes. A mechanical agitation is thus imparted to the columns of oil in the pipes 18, which materially assists in the disintegrating action of the heat to which the oil is subjected in the pipes 18, 50 and when passing from the tank 16 to the tank 20. While the perforations 50 permit the passage of oil upward therethrough, they also serve as means for the passage 55 downward through the pipes 18 of the carbon deposit or other residual or heavy matter eliminated from the oil under treatment.

As above stated, this heavy material is removed from the tank 16 through the man-hole 27. A certain proportion of heavy oil 60 also settles in the tank 16, and this may be

drawn off by the pipe 51. It will be noted that the construction employing the pipes 18 for suspending the tank 16, provides for preventing buckling of the said pipes, the weight of the tank 16 being sufficient to 70 maintain the straight-line arrangement of said pipes.

Claims:

1. A still comprising a heater having a fire-box, a delivery flue, and a heating chamber of relatively enlarged proportions intermediate said fire-box and flue; a receiving tank supported on said heater above said chamber and removed from contact therewith; a delivery tank disposed below said chamber and removed from contact therewith; and a plurality of transfer pipes operatively connecting said tanks, said pipes extending through said chamber for suspending the delivery tank from the receiving tank, said pipes being exposed to the heat products generated in said fire-box and delivered to said flue. 85

2. A still comprising a heater having a fire-box, a delivery flue, and a heating chamber of relatively enlarged proportions intermediate said fire-box and flue; a receiving tank supported on said heater above said chamber and removed from contact therewith; a delivery tank disposed below said chamber and removed from contact therewith; a plurality of transfer pipes operatively connecting said tanks, said pipes extending through said chamber for suspending the delivery tank from the receiving tank, said pipes being exposed to the heat products generated in said fire-box and delivered to said flue; and means mounted in each of said pipes for mechanically preventing by removal, coking or adhesion to 10 the sides of said pipe of the material under treatment. 95

3. A still comprising a heater having a fire-box, a delivery flue, and a heating chamber of relatively enlarged proportions intermediate said fire-box and flue; a receiving tank supported on said heater above said chamber and removed from contact therewith; a delivery tank disposed below said chamber and removed from contact therewith; a plurality of transfer pipes operatively connecting said tanks, said pipes extending through said chamber for suspending the delivery tank from the receiving tank, said pipes being exposed to the heat products generated in said box and delivered to said flue; and a plurality of mechanically operated devices, each suspended in one of said pipes for scraping said devices to prevent accumulations within said 11 pipes. 11

4. A still comprising a heater having a fire-box, a delivery flue, and a heating chamber of relatively enlarged proportions intermediate said fire-box and flue; a re- 12

ceiving tank supported on said heater above said chamber and removed from contact therewith; a delivery tank disposed below said chamber and removed from contact therewith; a plurality of transfer pipes operatively connecting said tanks, said pipes extending through said chamber for suspending the delivery tank from the receiving tank, said pipes being exposed to the heat products generated in said fire-box and delivered to said flue; a plurality of rods, one mounted within each of said pipes; and a plurality of series of disks mounted on said rods for scraping the inner sides thereof for preventing accumulations thereon.

5. A still comprising a heater having a fire-box, a delivery flue, and a heating chamber of relatively enlarged proportions intermediate said fire-box and flue; a receiving tank supported on said heater above said chamber and removed from contact therewith; a delivery tank disposed below said chamber and removed from contact therewith; a plurality of transfer pipes operatively connecting said tanks, said pipes extending through said chamber for suspending the delivery tank from the receiving tank, said pipes being exposed to the heat products generated in said fire-box and delivered to said flue; a plurality of rods, one mounted within each of said pipes; and a plurality of series of disks mounted on said rods for scraping the inner sides thereof for preventing accumulations thereon, said disks being provided with a series of openings therethrough permitting the passage of the material under treatment and residuum separated therefrom.

6. A still comprising a heater having a
40 fire-box, a delivery flue, and a heating
chamber of relatively enlarged proportions
intermediate said fire-box and flue; a receiv-
ing tank supported on said heater above
said chamber and removed from contact
45 therewith; a delivery tank disposed below
said chamber and removed from contact
therewith; a plurality of transfer pipes op-
eratively connecting said tanks, said pipes
extending through said chamber for sus-
50 pending the delivery tank from the receiv-
ing tank, said pipes being exposed to the
heat products generated in said fire-box and
delivered to said flue; a plurality of rods,
one mounted within each of said pipes; a
55 plurality of series of disks mounted on said
rods for scraping the inner sides thereof for
preventing accumulations thereon, said
disks being provided with a series of open-
ings therethrough permitting the passage
60 of the material under treatment and re-
siduum separated therefrom; and a recipro-
cating mechanism for said rods.

7. A still comprising a heater having a fire-box, a delivery flue, and a heating chamber of relatively enlarged proportions.

intermediate said fire-box and flue; a receiving tank supported on said heater above said chamber and removed from contact therewith; a delivery tank disposed below said chamber and removed from contact therewith; a plurality of transfer pipes operatively connecting said tanks, said pipes extending through said chamber for suspending the delivery tank from the receiving tank, said pipes being exposed to the heat products generated in said fire-box and delivered to said flue; a plurality of rods, one mounted within each of said pipes; a plurality of series of disks mounted on said rods for scraping the inner sides thereof for preventing accumulations thereon, said disks being provided with a series of openings therethrough permitting the passage of the material under treatment and residuum separated therefrom; and a reciprocating mechanism for said rods, said mechanism embodying a rocking shaft; a series of walking beams mounted thereon, and power-driven means for rocking said shaft.

8. A still comprising a heater having a 90
fire-box, a delivery flue, and a heating chamber of relatively enlarged proportions intermediate said fire-box and flue; a receiving tank supported on said heater above said chamber and removed from contact therewith; a delivery tank disposed below said chamber and removed from contact therewith; a plurality of transfer pipes operatively connecting said tanks; said pipes extending through said chamber for 100 suspending the delivery tank from the receiving tank, said pipes being exposed to the heat products generated in said fire-box and delivered to said flue; a plurality of rods, one mounted within each of said pipes; a 105 plurality of series of disks mounted on said rods for scraping the inner sides thereof for preventing accumulations thereon, said disks being provided with a series of openings therethrough permitting the passage 110 of the material under treatment and residuum separated therefrom; a reciprocating mechanism for said rods, said mechanism embodying a rocking shaft, a series of walking beams mounted thereon, and power-driven means for rocking said shaft; and means for condensing the vapors delivered 115 from said receiving tank.

9. A still comprising a heater having a fire-box, a delivery flue, and a heating chamber of relatively enlarged proportions intermediate said fire-box and flue; a receiving tank supported on said heater above said chamber and removed from contact therewith; a delivery tank disposed below said chamber and removed from contact therewith; a plurality of transfer pipes operatively connecting said tanks; said pipes extending through said chamber for suspending the delivery tank from the receiving tank.

1 tank, said pipes being exposed to the heat products generated in said fire-box and delivered to said flue; a plurality of rods, one mounted within each of said pipes; a plurality of series of disks mounted on said rods for scraping the inner sides thereof for preventing accumulations thereon, said disks being provided with a series of openings therethrough permitting the passage 10 of the material under treatment and residuum separated therefrom; a reciprocating mechanism for said rods, said mechanism

embodying a rocking shaft, a series of walking beams mounted thereon, and power-driven means for rocking said shaft; means 15 for condensing the vapors delivered from said receiving tank; and a sight gage for ascertaining the condition of the refined product.
